BALL POINT PEN

Walter G. Schoeman, Englewood, N. J., assignor to Ferber Corporation, Bergen County, N. J., a corporation of New Jersey

Application December 14, 1956, Serial No. 44,205

Term of patent 14 years

(Cl. D74—17)

FIG. 1.

FIG. 2.

FIG. 3.

FIG. 4.

FIG. 5.

FIG. 6.

FIG. 7.

FIG. 8.

FIG. 9.

Fig. 1 is a front view of a ball point pen showing my new design;

Fig. 2 is a side view thereof;

Fig. 3 is a top view thereof;

Fig. 4 is a view of the external contour thereof taken on line 4—4 of Fig. 2;

Fig. 5 is a view of the external contour thereof taken on line 5—5 of Fig. 2;

Fig. 6 is a view of the external contour thereof taken on line 6—6 of Fig. 2; Fig. 7 is a view of the external contour thereof taken on line 7—7 of Fig. 2; Fig. 8 is a view of the external contour thereof taken on line 8—8 of Fig. 2; and Fig. 9 is a view taken on line 9—9 of Fig. 2.

I claim:

The ornamental design for a ball point pen, as shown.
